UNITED STATES PATENT OFFICE.

GEORGE F. HOGAN, OF CHICAGO, ILLINOIS.

SANITARY-DRINKING-CUP BLANK.

1,021,099.

Specification of Letters Patent. Patented Mar. 26, 1912.

Application filed April 22, 1911. Serial No. 622,684.

To all whom it may concern:

Be it known that I, GEORGE F. HOGAN, a citizen of the United States, residing at Chicago, county of Cook, State of Illinois, have 5 invented certain new and useful Improvements in Sanitary-Drinking-Cup Blanks, of which the following is a specification.

The main object of my present invention is to provide a flat blank of paper or other 10 suitable material so cut and scored that it may be folded up into a drinking cup.

The details of my invention will be better understood by reference to the following description taken in connection with the accompanying drawings.

In the drawings, Figure 1, is a view of the top edge of the blank showing two of the scorings; Fig. 2, shows the whole blank; Fig. 3, shows a side edge; Fig. 4, is a perspective view of the cup made from one of the blanks, and Fig. 5, is a side elevation of said cup.

In the construction shown, the blank is of sectoral shape and preferably is of heavy 25 weight sulfite paper having a "water finish" and super-calendered. This paper is sufficiently resistant to water and has the advantage of freedom from oil, wax and other dust-collecting ingredients. Its high 30 finish contributes to cleanliness and is of material assistance to ready distribution of the blanks through automatic vending machines.

During the process of manufacture, the 35 sectoral blank is passed through a scoring machine to produce two radial scores 1 and 2 which intersect at the apex 3 of the segmental blank and which divide the blank into a central portion 4 and two side portions 5 and 6, all of the same size and shape. The outer or upper edges 7, 8 and 9 of these 40 several portions may be cut away slightly to improve the general shape of the finished cup. In addition to the radial scoring, the 45 blank has a machine-made, embossed transverse score which extends in a straight line across the lower ends of the segmental portions 4, 5, and 6. At 10, this transverse scoring forms the line on which the lower 50 corner of the blank may be folded up, but at

11 and 12, the scoring has another function as hereinafter set forth.

The scored blank above described may be regarded as the finished product, or article of manufacture, and is sold ordinarily in 55 this flat and unfolded condition. To fold it into a cup, one of the side portions is folded over onto the central portion, with which it exactly corresponds in size and shape, and then the second side portion is folded over 60 on the other two. It makes no difference which side portion is folded in first, since they are exactly alike. This is an important feature when the blanks are to be used by school-children and others who could not 65 economically be taught a complex folding operation. To complete the cup, it is only necessary to fold up the lower corner or apex 3, along the line 10.

To open the cup for filling, it is only necessary to squeeze it in the hand. The stiffness of the paper will cause the sides to bulge outward and, furthermore, will force the edge of the inner side portion 6, tightly 75 into the corner of the cup, where it will make a substantially water tight joint. But during this squeezing operation, the side scorings 11 and 12 play an important part. As previously recited, the paper is stiff and the scorings are machine-made; as the result, the paper tends to buckle or pucker along the scorings 11 and 12 and this serves 80 automatically to open up the lower portion of the cup and also to crowd the paper downward at the bend 10, thereby tightening the 85 fold and making it secure.

What I claim as new and desire to secure by Letters Patent of the United States is:—

A flat blank for a drinking cup, said blank consisting of stiff waterproof paper 90 cut to sectoral form and having two radial scorings which divide said blank into three equal portions of uniform shape, said portions being so disposed that when either side portion is folded over the intermediate 95 portion, the entire edge of said side portion will rest on the opposite scoring, said blank also having an embossed transverse score which extends in a straight line across all three portions of the unfolded blank ad- 100

ja⁵cent to the lower corner of the sector, said transverse score being so positioned on the intermediate portion of the blank as to serve as a line for folding, and being so positioned on the side portions as to pucker said side portions when said blank is folded up squarely at its lower corner to form a cup.

In witness whereof, I hereunto subscribe my name this 20th day of April 1911.

GEORGE F. HOGAN.
